UNITED STATES PATENT OFFICE.

ROBERT BLAISDELL MAGUNE, OF ROCKLAND, MAINE.

PERFORATING DEVICE.

Application filed October 16, 1926. Serial No. 142,025.

This invention relates to a perforating device.

An object of the invention is to provide a perforator which can be applied to a printing machine and can be permanently secured thereto without in any way affecting the operation of the machine as a printing machine and so related to the rest of the machine that perforation takes place only when desired.

A further object is to provide means whereby a printed sheet which is also to be perforated can be very accurately alined with respect to the perforator.

The invention is illustrated in the drawings, of which—

Figure 1 is a partial section through a perforator device employing part of my invention;

20 Figure 2 is a plan view thereof;

Figure 3 is a side elevation of one end of the perforator device with the auxiliary or marking button in place;

25 Figure 4 is a section on the line 4—4 of Figure 3;

Figure 5 is a section on the line 5—5 of Figure 1;

30 Figure 6 is a partial end section showing the operating button in the position in which it operates the perforator;

Figure 7 is a section of the operating button by itself.

The form of the invention shown in the drawings is a preferred form, although it is understood that modifications in the construction and arrangement of the parts and in the character of materials used may be adopted without departing from the spirit of the invention as set forth in the appended 40 claim.

In its general aspect the invention is employed in connection with the usual perforator bar having a spiral on one end operated by connection with the pivot lever, 45 which in turn is connected to an operating plunger. This plunger is adapted to be actuated through the operation of the ordinary pressure plate of a printing press or machine.

In my invention, however, the plunger does 50 not in any position extend above the top of the base on which it is mounted. It is never more than flush with the top of the base and in order to be operated requires contact with an operating button which is 55 adapted to be mounted on the pressure plate, preferably disposed in a predetermined po-

sition on the tympan sheet which is ordinarily adjustably registered on the face of the pressure plate. The location of this operating button on the pressure plate is determined by first disposing on the perforator and over the plunger a temporary button alined with the plunger, the upper surface of which button is coated with ink so that as the pressure plate is moved downward the contact between the upper surface of this button and the surface of the tympan sheet will mark on said sheet the point over which the operating button is to be centred, so that when the pressure plate is depressed it will be alined properly with the plunger which it is to operate.

When it is desired merely to print and not to perforate, all that is required is to remove the operating button from the pressure plate, which can then move down toward the perforator without actuating the plunger on the perforator, because said plunger lies beneath or not more than flush with the surface of the perforator.

The invention further recites in particular means whereby a temporary marking button can be attached to and removed from the perforator.

In the preferred form of the invention shown in the drawings, I provide a perforator base 10, the upper surface of which is provided with a longitudinal recess 11 adapted to receive a perforating bar 12 having a rounded lower edge 13, concave sides 14 which merge into a series of perforating or scoring teeth 15. One end of this perforator bar is provided with a pin 16 journaled preferably in a plate 17 adjustably fastened against the end of the block. The other end of the perforator bar is provided with a spiral element 18 journaled in the wall of a cylinder 19. The cylinder 19 is secured to the base 10 by pins 20 in the present instance, although it may be made integral with the base. A pin 21 acts as a pivot for a lever 22, one end of which is in the form of a yoke 23 embracing spiral 18 and the other end of which is notched as at 24 to receive a lip 25 on the lower end of a plunger 26, located in a bore 27 of the cylinder 19. A spring 28 arranged inside of the plunger 26 has a normal tendency to force the plunger upwardly and allows it to move downwardly. The top of the plunger 26 is concave and the relation of the plunger to the parts of the perforator with which it is associated and thus

far described, is such that the top of the plunger never extends above the highest part of the cylinder 19. The top wall of the cylinder is provided with a transverse groove 30 and lateral grooves 31 and 32. Wires 33 and 34 are adapted to be inserted in the lateral grooves and are connected at their opposite ends together and to a spring wire or blade 35 supporting a marking button 36, the lower face 37 of which is convex and the upper face 38 of which is flat preferably and adapted to receive ink. This marking button mounted on these wires, which can be quickly associated with the cylinder 19, is adapted only temporarily to be connected with the perforator and when so connected is disposed directly over the top of the plunger 26. When the marking button is in position the pressure plate 39 is brought down, this pressure plate being preferably provided with a filler or backing face 40 and the usual tympan sheet 41. As this tympan sheet contacts with the upper surface of the marking button 36 an ink mark is made on the sheet, which indicates the point of alinement with the axis of the button 36. The marking button 36 is then removed and an operating button 42 with a flat face 43 and a convex bottom 44, shown in Figures 6 and 7, is centered over this ink mark on the tympan sheet by means of a pin 45 and a lateral attaching means 46 which may be a spring, a wire or any other suitable device which can be engaged with the tympan sheet to hold the operating button thereon. The operating button 42 is therefore alined with the axis of the plunger 26 when the pressure plate is moved downwardly and consequently will actuate this plunger to move the yoke 23, thus turning the perforator bar 12 to its upright position by virtue of the action of the spiral 18.

It is obvious, however, that if the operating button 42 is not mounted in association with the plunger 26 the perforator is not actuated. Therefore, by providing a plunger on a perforator which will not extend above the surface of its socket, I can leave the perforator attached to the machine when ordinary printing without perforation is to be done. I can effect perforation at any time merely by attaching the operating button to the pressure plate, preferably to the tympan sheet which has previously been marked in the manner described by the use of a marking button, so as to enable the operating button to be accurately positioned. When the marking button 36 is depressed the transverse slot 30 will permit the wire 35, which supports said marking button, to go below the top surface of the cylinder 19 whereby the movement of the pressure plate of the printing machine will not be interrupted.

What I claim is:

A device to be used on a printing machine which comprises a pressure plate having a tympan sheet mounted on the front face thereof, a base, a rocker bar mounted on said base, said base having a bore therein, a compressible plunger in said bore, means connecting the plunger and the rocker bar, the uppermost position of the plunger bringing its upper edge flush with the upper surface of the base, an operating button having a rearwardly extending pin alined with the center of a mark on the tympan sheet and laterally extending fastening means on said button to fasten it to the tympan sheet, whereby as the pressure plate is moved upwardly toward the base of the printing machine the button will be in alinement with the bore and operate the plunger, whereby the operation of the rocker bar is achieved.

ROBERT BLAISDELL MAGUNE.
